UNITED STATES PATENT OFFICE.

IRA S. FISHER, OF MOLINO, MISSOURI.

RAIL-TIE.

1,221,714.

Specification of Letters Patent.

Patented Apr. 3, 1917.

Application filed November 11, 1916. Serial No. 130,844.

To all whom it may concern:

Be it known that I, IRA S. FISHER, a citizen of the United States, residing at Molino, in the county of Audrain and State of Missouri, have invented certain new and useful Improvements in Rail-Ties; and I do hereby declare the following to be a full, clear, and exact description of the invention, such as will enable others skilled in the art to 10 which it appertains to make and use the same.

This invention relates to metallic rail ties of the type formed of opposed spaced sections adapted to support the companion rails 15 of a track, and an object of the invention is to so construct each tie section that the same can be effectively anchored and held against movement.

Another object of the invention is the provision of a novel type of connecting means 20 for detachably and adjustably connecting the opposed sections of the tie to each other.

A further object of the invention is to provide the tie sections with novel rail securing 25 means that will admit of the rails of a track being conveniently and expeditiously clamped in operative position and effectively held against movement.

Other objects will appear and be better 30 understood from that embodiment of my invention of which the following is a specification, reference being had to the accompanying drawings forming a part thereof, in which:

Figure 1 is a side view of a rail tie constructed in accordance with my invention, showing the manner of mounting the same on a concrete ballast or roadbed,

Fig. 2 is a top plan view of Fig. 1,

Fig. 3 is a longitudinal sectional view 40 taken through the rail tie sections, showing a modified form of retaining means for the sections,

Fig. 4 is a top plan view of Fig. 3,

Fig. 5 is a perspective view of one of the tie sections removed from operative position,

Fig. 6 is a perspective view of one of the clamping plates for one of the rails of a track.

Referring to the drawings in detail, the letter A designates a concrete roadbed or ballast, having located on its upper surface, adjacent the opposite sides thereof, a pair of abutments B.

Disposed above the ballast or roadbed A is a rail tie formed of opposed adjustably

connected sections, which rest respectively, on the abutments B, and each section is designated, as an entirety, by the numeral 1. As the sections 1 are identical in construction a description of one is deemed sufficient for both. As shown in Fig. 5, each section is formed of a single casting, which is of rectangular shape and includes a top wall 2, bottom wall 3 and opposite end walls 4 and 5. A web 6 is interposed between the walls 2 and 3 and 4 and 5, and is disposed inwardly of the opposite side edges of the walls, as shown in Fig. 5. An extension 7 is formed on the lower end of the wall 5 and a substantially triangular shaped web 8 has connection with the wall 5 and the extension 7 and serves to reinforce both the extension and the wall. When the section, shown in Fig. 5, is in operative position on one of the abutments B, the extension 7 terminally extends beyond the adjacent side of the ballast A, as shown in Fig. 1, and the opening 9 receives the shank of an eye bolt 10, the upper end of the shank having turned thereon a nut 11 which is adjustable against the extension 7 and serves to hold the eye bolt in operative position. The head of the eye bolt is disposed below the under side of the extension and receives the upper bent end of an upwardly extending rod 12, the lower end of the rod 12 being coiled to provide an eye which receives the downwardly curved terminal of the outer end of a horizontally disposed rod 13, which is embedded in the concrete ballast or roadbed A, as shown in Fig. 1. The eye bolt 10 and the rods 12 and 13 serve to prevent upward movement of the adjacent tie section. The top walls 2 of the tie sections are disposed below the upper ends of the end walls 4 and 5, and form seats for the companion rails of a track, the said rails being designated by the letter C. Located on opposite sides of each rail C are a pair of clamping plates, designated, respectively, 14 and 15. The clamping plates 14 have their outer edges abutting against the inner surfaces of the walls 5, and have their inner ends provided with flanges which engage over the flange on the adjacent rail. Fastening bolts 16 extend through the clamping plates 14 and have their lower ends extended through openings in the top plates 2, and nuts 17 are adjustable on the lower ends of the bolts 16 and against the under surfaces of the plates 2. The clamping plates 15 are located at the inner side of the

base flanges of the rails and are provided with elongated slots 18, which receive fastening bolts 19, which have their lower ends extended through the top wall 2 and nuts 20 5 are turned on the lower ends of the bolts 19 and are adjustable against the under surface of the top wall 2. By virtue of the provision of the elongated slots 18 the clamping plates 15 can be moved either away or 10 toward the adjacent rails, without necessitating the removal of the bolts 19. The clamping plates 15 are provided with stems, as shown in Fig. 6, the said stems extending through openings in the walls 4 and are 15 threaded and the nuts 21 and 22 are adjustable on each of the stems carried by the clamping plates 15 and are located, respectively, on opposite sides of the walls 5. Each pair of nuts 21 and 22 coöperate to prevent 20 longitudinal movement of the adjacent stem upon which they are mounted, when the clamping plate carried by the adjacent stem has been moved to adjusted position. The inner ends of the plates 2 are offset down- 25 wardly, as shown at 22', to provide sufficient spaces for the nuts 21, so that the latter can be conveniently turned.

Extensions 23 are formed on the outer sides of the walls 4, adjacent the upper ends 30 thereof, and in line with the terminal of the offset ends of the plates 2, and have their free ends provided with diagonal openings 24. The openings 24 in the extensions 23 receive the upper ends of upwardly diverging rods 25, the upper terminals of the rods 25 extending through washers 26, and having nuts 27 turned thereon and adjustable against the washers 26 so as to hold the rods 25 against downward movement when in adjusted position. The lower ends of the rods 25 are bent to provide hooks, which receive the curved upper ends of a pair of vertically disposed rods 28, which are embedded in the concrete ballast or roadbed A. In 45 Figs. 1 and 2 of the drawings the sections of the tie are shown connected to each other by means of a pair of parallel rods 29. These rods 29 extend through openings 30 formed in the inner walls 4, and mounted 50 on each end of each rod 29 is a pair of washers 31, formed of fiber, and lying, respectively, on opposite sides of the adjacent end wall 4. The ends of the rods 29 are threaded, and mounted on each end of each rod 55 is a pair of nuts 32 and 33, which lie on opposite sides of the adjacent end wall 4 of the rail section, and are adjustable against the adjacent washers 31. The rods 29 adjustably connect the sections 1 to each other, and admit of the sections being moved in either direction to properly space the sections so as to accommodate the rails C of the track. In Fig. 1 of the drawings, each section 60 is shown provided with a rod 34, which has its forward end extended through an

opening in the inner end wall 4 of the adjacent section, at a point spaced below the openings 30, and terminally bent downwardly to provide a head 35 which engages the inner face of the adjacent abutment B. 70 The outer end of each rod 34 is bent upwardly, as shown at 36, and thence terminally continued horizontally from the upwardly bent portion 36 and threaded and extended through an opening in the outer end 75 wall 5 of the respective section, and has a nut 38 turned thereon adjustable against the outer surface of the adjacent outer wall 5. When the rods 34 are in operative position, the sections 1 of the tie are effectively 80 braced against outward movement, and by virtue of the employment of the rod 34, the rods 25, 28 and 29 will be relieved of considerable strain.

In Figs. 3 and 4 of the drawings the rods 85 29 are dispensed with. This is necessary when it is desired to place a water trough between the rail sections at a desired point. When the rods 29 are thus dispensed with, each section of the tie is provided with a 90 pair of rods 39. These rods 39 are identical in construction with the ones 34, shown in Fig. 1 of the drawings, but the rods forming each pair are extended in opposite directions, as shown in Fig. 3. The inner end of 95 one of the rods 39 extends through an opening formed in the inner wall 4, of the adjacent tie section, at a point above the lower wall 3 and is terminally bent to provide a head 40, which engages the inner face of the 100 adjacent abutment B, and the opposite end of the rod extends through an opening in the outer wall 5 and is threaded and has mounted thereon a pair of nuts 41, which lie, respectively, on opposite sides of the outer wall 105 5 and are adjustable thereagainst. The other of the rods 39 has its outer end extended through the outer wall 5 at a point below the outer end of the first-mentioned rod 39 and is terminally bent downward to provide 110 a head 42, which engages the outer face of the adjacent abutment B, and the last-mentioned rod 39 has its inner end extended through an opening in the inner wall 4, at a point above the inner end of the first-mentioned rod 39 and threaded and provided with a pair of nuts 43 which lie on opposite sides of the inner wall 4 and are adjustable 115 thereagainst.

By providing each tie section with a pair 120 of rods 39, as shown in Figs. 3 and 4 of the drawings, the tie sections will be effectively held against movement in a direction either toward or away from each other.

Located beneath the tie sections 1 are 125 blocks 44, which are constructed, preferably of wood, and serve to provide a cushion for the tie section. Fastening elements 45 extend through openings in the lower wall 3 of each of the tie sections, and through the 130

adjacent block 44 and are embedded in the concrete roadbed A, and serve to prevent displacement of the blocks 44.

It is evident, that various changes might 5 be resorted to in the construction, form and arrangement of the several parts without departing from the spirit and scope of the invention as claimed.

Having thus described my invention what 10 I claim as new, is:

1. A rail tie consisting of a pair of opposed sections each being formed of a single casting having upper, lower and opposite end walls, the said upper wall being disposed 15 below the upper ends of the end walls, rail fastening plates mounted on the upper wall of the section, one of the pair of rail fastening plates mounted on the upper wall of the section, one of the plates engaging the inner 20 surface of one of the end walls, and a stem carried by the other plate of the pair and adjustable through the other end wall of the section, for the purpose specified.

2. A rail tie consisting of a pair of opposed sections each being formed of a single casting having upper, lower and opposite end walls, the said upper wall being disposed 25 below the upper ends of the end walls, rail fastening plates mounted on the upper wall of each section, one of the plates on each section engaging the inner surface of one of the end walls, the other plate having an elongated slot therein, a bolt extending through 30 the elongated slot in the last-mentioned plate 35 and through the upper wall of the section, and means adjustably connecting the last-mentioned plate to the other end wall of the section.

3. A rail tie consisting of opposed sections, each being formed of a single casting having upper, lower and opposite end walls, an extension formed on the lower end of one of the end walls and having an opening 40 therein, a second extension formed on the

other end wall, adjacent the upper end thereof, and having an opening therein, and a reinforcing web having connection with one of the extensions and the adjacent end wall. 45

4. A rail tie formed of a pair of opposed sections, each of the sections being formed of a single casting having upper, lower and opposite end walls, the opposing walls of the sections having openings therein, a pair of parallel rods interposed between the sections and having their opposite ends threaded and received by the openings in the opposing walls of the sections, and means for normally preventing a relative movement between the rail sections and the rods. 50 55

5. In a railway roadbed construction, the 60 combination with a ballast, of a rail tie mounted on the ballast and formed of opposed sections, each of the sections having an upper, a lower and an opposite end wall, extensions formed on the end walls of both 65 sections, upwardly extending rods connected to the extensions on the sections, and rods secured to the ballast and having connection with the lower ends of the first-mentioned rods. 70

6. In a railway roadbed construction, the combination with a ballast having abutments formed on the upper surface thereof, of a rail tie formed of opposed sections resting, respectively, on the abutments, each of the 75 sections consisting of an upper, a lower and opposite end walls, rods extending through the rail sections and having their ends extending through openings in the end walls, and heads formed on the rods and engaging 80 the sides of the abutments, for the purpose specified.

In testimony whereof I affix my signature in presence of two witnesses.
